UNITED STATES PATENT OFFICE.

MILTON B. REACH, OF CHICOOPEE, MASSACHUSETTS.

PLAYING CARDS.

1,418,020.

Specification of Letters Patent. Patented May 30, 1922.

Application filed June 8, 1921. Serial No. 475,998.

To all whom it may concern:

Be it known that I, MILTON B. REACH, a citizen of the United States, and resident of Chicopee, in the county of Hampden and State of Massachusetts, have invented certain new and useful Improvements in Playing Cards, of which the following is a specification.

In the playing of duplicate bridge, whist, or like games where the players are scoring against "par" or against the score of other players on a predetermined hand or series of predetermined hands it is important that the players be relieved from mental effort or strain in dealing the cards or keeping track of the deals or of the rotation of the hands, so that each player may devote himself mainly to the game itself, and not have his attention diverted by the handling of paraphernalia or by more or less complex plans of dealing.

In carrying out my invention, I provide what I term a direction indicator to indicate at sight and without mental effort whether the card is to go to the player at the dealer's right, left, to himself or opposite, and this indicator is of such a character as to indicate location in respect to the dealer and not of that character, such as a number or letter, which necessarily must change from player to player as the successive hands are dealt, and thus require closer attention to avoid confusion and error, particularly on the part of the less experienced players.

Other features of my invention will be fully described hereinafter, and particularly pointed out in the claims.

The drawing shows in Fig. 1 the back of a playing card made according to my invention.

Fig. 2 indicates a blank showing one of the stages in making the card of Fig. 1.

Fig. 3 is an enlarged view of a portion of the card to show the background, which is omitted from Fig. 1.

Fig. 4 is a view of a card to be placed in the pack in a sealed envelope. By reason of the limitations of space, I have attempted to show only a part of the data which such an element would bear in actual practice.

Fig. 5 illustrates another card bearing data as to the handicap allowed.

In the manufacture of the cards I first make up in large quantity blanks such as

shown in Fig. 2, which have impressed thereon a suitable color background and also symbols, as numbers or letters in numerical or alphabetical order, to designate the rotation of hands. For instance, the numeral 1 would indicate the first hand played or in other words, the first round of play, the numeral 2 the second rotation of the hands and so on.

In the present instance, the card would bear four series or groups of symbols, two of these series being at the top of the card and the other two in reversed position at the bottom of the card, and in the present instance each series runs from 1 to 9, indicating that eighteen different hands or rounds may be played.

These blanks are kept in storage by the manufacturer and when a number of packs are to be marked, having indications thereon for the desired predetermined hands, the desired number of packs of blanks are withdrawn from storage and upon their backs and in proper relation to the indices, as 1, 2, 3, etc., or letters A, B, C, etc., already printed thereon, the deal location indicators and symbol enclosures are printed.

The manufacturer is thus enabled, in an economical manner, to place on the market a great variety of games, one set following the other at proper intervals, so that the market may be kept active by bringing out packs with new hands to take the place of those which have become more or less stale, all of the packs being printed from the blanks previously prepared.

The deal indicators are preferably in the form of pointers, such as *a*, which indicates at a glance the direction in which the card must be dealt. For instance, if hand or round number 1 is being dealt, the card illustrated would be dealt to the dealer. If hand or round number 2 was being dealt, the same card would go to the player at the dealer's right, because in the first instance, the indicator *a* points to the dealer, whereas in the second instance mentioned, the indicator points towards the right. In the hand number 3, the card would go to the dealer's partner, so also it would do so in deal number 4. In deal number 5 the card would go to the player at the dealer's left.

These pointers form portions of markings which divide up the field of display into a

number of enclosures in which the indices first mentioned are located. These enclosures in the present instance are provided by circles *b* or segments of circles, which 5 connect with the pointers. These pointers are printed preferably in solid color and they are in the general form of the head of an arrow. The markings above described, in turn, may be enclosed with comparatively 10 heavy border lines *c* of rectangular formation, but with a break at the point where the direction indicator is located.

These enclosures serve to concentrate the 15 vision to the indices included within them, and they bring the two kinds of indices into intimate association in pairs. The cards may be decorated in any suitable way, and in the drawing a space in the general form 20 of a cross has been shown, in which any desired picture or design may be printed.

In the dealing of the cards, the dealer without effort is enabled to place them with the proper players, and he does not have to 25 keep in mind any arbitrary plan of differentiation, as would be the case if, say, a combination of letters and figures were used. In such case the letters indicate one thing and the numbers another, and a careless or indifferent player may become confused and 30 reverse the indications. With the pointers, however, this cannot occur. It will be noticed that each player is left free to exercise his own judgment in laying down the cards. There is no indicator as to the plays 35 which are to be made, and thus the relative skill of the players determines the outcome of the game.

It will be clear that the markings on the 40 card taken with the colored background enter into the design and distinctive and pleasing effects may be secured.

The pointers are inherently indicative of the direction in which the cards must be dealt, and are thus distinguished from arbitrary letter and numeral indications.

Auction bridge is now played in the following manner: The cards are shuffled, then dealt into four individual hands of thirteen cards each, the value of the individual hands 50 is appraised by the individual players holding those cards, and by a system of bidding each player is privileged to contract to take so many tricks. He is guided in his contract by the cards which he holds and knows 55 the value of under ordinary circumstances, by the bidding of his opponents which enables him through inference to possibly locate certain cards in his opponents' hands, to his right or left, that may increase the 60 value of his own hand, and by a law of averages that in any ordinary distribution of cards he could reasonably count on at least two tricks in his partner's hand. Hence, if the original bidder sees within his own hand 65 six reasonably assured tricks, counting on

an average of two tricks in his partner's hand would justify him in making a contract to take eight tricks. If he went this far and his partner raised his bid one or two more, that would be an indication that his 70 partner had that many more tricks over and above the average counted on.

These hands, of course, vary greatly in the distribution of cards. A game consists of thirty points. Different suits have different 75 values. Clubs count 6 points to the trick; diamonds, 7 points; hearts, 8 points; spades, 9 points; no trump, 10 points. It will be seen that a bidder with a strong club hand must take five tricks for game, also the 80 diamond hand; hearts, 4 tricks; spades, 4 tricks; no trump, 3 tricks. Now it is conceivable that an individual hand may be good for five hearts or 40 points that will go game by taking four tricks. In other words, 85 an error may occur in play but the margin of safety still enables the player to go game.

To offset this distribution of luck and to compare equalities of play, the game of duplicate auction was devised. This game is 90 played just like regular bridge only there is a board containing four compartments to hold the separate hands which are kept separate as played, and after a certain number of boards have been played, whatever number 95 may be decided upon at the beginning, they are shuffled up, drawn at random, and are replayed with opposing players taking each other's hands. In this game there is, of course, a reward for better play and an 100 opportunity for one pair of players to correct and profit by the mistakes of the other pair. However, the standard of play is the respective skill of the players and varies accordingly. The score is the difference between the two sets of play. In other words, 105 a series of boards must be played before a standard can be determined, and as above stated, this standard may be faulty.

In the game which I propose, the original 110 hands are all compiled in advance of the manufacture of cards. The weak and the strong hands are each correctly judged and appraised according to sound rules of bridge. These hands are then reproduced 115 on the back of the card in the preferred form which my invention shows, and the opposing players then play against a fixed perfect score for each group of hands, weak and strong. In addition to this they have 120 the opportunity of replaying the cards as in duplicate bridge.

Each pack of cards will contain a supplementary card within the pack that records the value in points of each hand which may 125 be designated as north and south, east and west. This card will be placed in a sealed envelope and it would not be referred to until the hands have been played. Then the score of those hands would be checked up 130

against the true score to learn where the errors occurred.

It will be noted that this memoranda gives the par score for intermediate stages of the game, and the players, if the score made is below par can play over that part of the game and seek to attain par without waiting to play the whole game before repeating.

On the box containing the cards or on the label within the box, or on a separate card to be placed in the pack, a statement would be made somewhat as follows: "The master hands in this pack lie north and south, the eighteen hands being good for 2,000 points; the east and west hands are good for 1,800 points." So that the players in sitting down to play would know that east and west were to receive a handicap of 200 points to properly balance their respective play.

It will be noticed that in my present embodiment of the invention the indices for the direction of the deal are located at different sides of the indices for the rotation of hands. Thus the deal index *a* for the hand rotation index 1 is below it. The deal direction index for the index 2 is at its right, and the deal direction index for the index 3 is above it and so on throughout the series.

I claim:—

1. A playing card having the back surface thereof divided into a multiplicity of enclosed areas with deal indicating symbols alike in character located thereat, each of said symbols being one of a series corresponding in number to the number of rotations of the hands, the directions of the deals being indicated by the different locations of the symbols in respect to said enclosed areas.
2. A playing card having the back surface thereof provided with indices for the rotation of the hands, each index being enclosed by a line having at one point a deal direction indicator, substantially as described.
3. A pack of playing cards having on the back of each of the cards a plurality of symbols, one for each rotation of the hands and positioned in consecutive order corresponding with the order of the rotation of the hands, each symbol pointing in the direction the card is to be dealt in the particular one of the rotations of the hands to which the symbol belongs, and when the pack is held in position for dealing, substantially as described.
4. A playing card having indices on its back for the rotation of the hands, and other indices inherently indicative of the direction in which the card must be dealt in the different hands, each of the first mentioned indices having one of the last mentioned indices associated therewith, substantially as described.
5. A playing card having indices on its back for the rotation of the hands, and other

indices inherently indicative of the direction in which the card must be dealt in the different hands, said direction indices consisting of pointers, substantially as described.

6. A playing card having a series of indices on its back for the rotation of the hands, markings individual to said indices enclosing the same, and indices for the direction of the deals associated with said indices first mentioned and with the enclosure markings, substantially as described.

7. A playing card having a series of indices on its back for the rotation of the hands, markings individual to said indices enclosing the same, and indices for the direction of the deals associated with said indices first mentioned and with the enclosure markings, said direction indices consisting of pointers, substantially as described.

8. A playing card having the back thereof marked with a multiplicity of symbols for regulating the rotation of hands, each symbol being placed within a separate enclosure having a pointer portion to indicate the direction in which the card is to be dealt in the particular rotation of the hands to which the symbol and enclosure belongs.

9. A playing card having as part of its foundation printing a series of indices for regulating the rotation of the hands, and registering therewith individual design patterns indicating the direction of the deals.

10. A playing card having on its back indices for the rotation of the hands and other indices for the direction of the deals, the latter indices being of like form but differently disposed, substantially as described.

11. A pack of playing cards each having indices on its back for the rotation of the hands and other indices for the direction in which the cards are to be dealt, and a member associated with the pack of cards bearing thereon memoranda relative to the par value of the hands, substantially as described.

12. A pack of playing cards each having indices on its back for the rotation of the hands and other indices for the direction in which the cards are to be dealt, and a member associated with the pack of cards bearing thereon memoranda of the value of the hands, north, south, east and west, said member being sealed from view and to be opened to view after the hands have been played so that the scores attained by the players can be checked up with the scores indicated by the memoranda, substantially as described.

13. A pack of playing cards each having indices on its back for the rotation of the hands and other indices for the direction in which the cards are to be dealt, and a member associated with the pack of cards having thereon a memorandum of the handi-

cap in points which a certain player or places must receive in order to balance the normal or par value of the hands.

14. A playing card having on its back 5 indices for the rotation of the hands and other indices for the direction of the deals, the latter indices being of like form but disposed at different points relative to the first indices, that is to say, the deal index belonging to one hand rotation index is at a 10 different location in respect thereto as compared with the location of deal indices of other hand rotation indices in the same series, substantially as described.
15. 15. A playing card having on its back 15 indices for the rotation of the hands and other indices for the direction of the deals, the latter indices being of like form but disposed at different points relative to the first 20 indices, that is to say, the deal index belonging to one hand rotation index is located on a different side thereof as compared with the location of deal indices of other hand rotation indices in the same series.
25. 16. A pack of playing cards each having a series of indices on its back for the rotation of the series of hands in the game, and other indices for the direction in which the cards are to be dealt, and a member asso-

ciated with the pack of cards bearing thereon memoranda relative to the value of hands at intermediate stages of the game, substantially as described.

17. A playing card having on its back 30 a series of indices indicating the rotation of 35 the hands, and markings enclosing the said indices and having either at top, bottom, right or left of said indices a pointer portion, substantially as described.

18. A playing card having on its back a 40 series of indices for the rotation of the hands with a line for each index enclosing the same, each of said lines merging into a thickened pointer portion, substantially as described.

19. A pack of playing cards each having 45 on its back a plurality of markings, one for each hand rotation, and a symbol for each marking associated therewith, the said symbols being disposed at different points about the hand rotation markings for indicating the direction of the deals, the deal symbol belonging to one hand rotation marking being at a different location in respect thereto as compared with the location of deal symbols of other hand rotation markings in 50 55 the same series, substantially as described.

In testimony whereof I affix my signature.
MILTON B. REACH.
